UNITED STATES PATENT OFFICE

MYRL HARRISON, OF CINCINNATI, OHIO, ASSIGNOR TO THE KURZ-KASCH COMPANY,
OF DAYTON, OHIO, A CORPORATION OF OHIO

DESIGN FOR A CONTAINER LID

Application filed February 6, 1932. Serial No. 42,762. Term of patent 7 years.

To all whom it may concern:

Be it known that I, MYRL HARRISON, a citizen of the United States, residing at Cincinnati, Hamilton County, Ohio, have invented a new, original, and ornamental Design for a Container Lid, of which the following is a specification, reference being had to the accompanying drawing, forming a part hereof.

In the drawing Fig. 1 is a top plan view of a container lid embodying my new design.

Fig. 2 is a side elevation of the container lid. The dominant feature of the design comprises multiple segments, some of which are grouped concentrically and others of which are grouped in radiating relation.

I claim:

The ornamental design for a container lid substantially as shown and described.

In testimony whereof, I have hereunto set my hand this 30th day of January, 1932.

MYRL HARRISON.
